Frank J. Hage, Inventor
By George E. Geddes, Attorney

UNITED STATES PATENT OFFICE.

FRANK J. HAGE, OF GOLDSBORO, NORTH CAROLINA, ASSIGNOR OF ONE-HALF TO ALBERT A. JOSEPH, OF GOLDSBORO, NORTH CAROLINA.

FASTENING DEVICE.

1,321,368.

Specification of Letters Patent. Patented Nov. 11, 1919.

Application filed July 31, 1919. Serial No. 314,522.

To all whom it may concern:

Be it known that I, FRANK J. HAGE, a citizen of the United States, residing at Goldsboro, in the county of Wayne and State of North Carolina, have invented new and useful Improvements in Fastening Devices, of which the following is a specification.

This invention relates to improvements in fastening devices and more particularly to those fasteners used to bind or grip together a plurality of tobacco stalks or leaves. Heretofore it has been the practice to bind the hanks or hands of tobacco leaves, as they are harvested, by wrapping and tying them with a tobacco leaf, which binding or wrapper is supposed to stay fixed all during the period that the tobacco is in the hands of the farmer, while it is in the warehouse, while it is being dried or cured and up until the time it is manufactured into articles ready for sale. It is needless to say that such a practice is exceedingly faulty, as the wrapper of tobacco leaf does not stay fixed but falls apart, thus allowing the leaves comprising the hank or hand to become scattered. It very often happens that the warehouse men are obliged to employ extra help to have the tobacco retied, thus securing to the farmer a lesser amount for his product on account of this extra expense. This invention, it will be seen, avoids these disadvantages and provides a simple, secure and inexpensive binder or fastener, which stays fixed from the time the leaves of tobacco are first cut up to the time the tobacco is manufactured into finished articles by the factoryman.

In the drawings:

Figure 1 shows the device secured to a hank or hand of tobacco leaves.

Fig. 2 is a cross section through the line 2—2 of Fig. 1.

Fig. 3 shows the device before it is applied to the tobacco leaves.

Fig. 4 is a modification, showing the blank as it is first stamped out.

The invention consists of a longitudinally

concave strip *a*, converging slightly at the middle as indicated by *b*. At one end of the strip *a* is a wire *c*, passing through the holes *d*, *d*, and being bent at each end to form the eyes *e*, *e*. At the other end of the strip *a* is a wire *f* passing through the holes *g*, *g*. 55

The bundle of tobacco leaves are gathered and the strip *a* is bent at the point *b* so as to inclose the ends of the stalks as shown in Fig. 1. The ends of the wire *f* are then passed through the eyes *e*, *e* and are then brought around the back of the end of the strip *a* and are fastened or twisted as shown at *h* in Fig. 1. This provides a simple device, capable of being attached and detached quickly and makes a secure fastener, 65 so that at no time are the leaves scattered or lost.

The fastener or grip may be of any number of substances, such as compressed paper, paste board, tin, aluminum, zinc or a composition. 70

The modification shown in Fig. 4 shows the device just as it is stamped and before it is turned into a concave shape. It has the main strip *i* converging at the middle 75 and adapted to be bent at *j*. After it is bent around the tobacco stalks, the tongue *k* is passed around the bundle and through the slot *l* and then is bent flat so as to hold it in place, the invention being the same, but 80 in which the tongue *k* and slot *l* are substituted for the wire *f* and the wire *c* having the eyes *e*, *e*.

What I claim is:

A longitudinally concave strip adapted to be bent around the material to be fastened together, a wire at one end of said strip, said wire being formed into an eye at each end thereof and a wire at the other end of said strip, the ends of said latter 85 wire being adapted to pass through the corresponding eyes at the other end of the strip, when the said strip is bent, and then to be brought around the end of the said strip and fastened together. 90

FRANK J. HAGE.
